(57) **CLAIM**

The ornamental design for an water flosser as shown and described.

DESCRIPTION

FIG. 1 is a perspective view of an water flosser showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of the water flosser, shown in a configuration of use.

FIG. 10 is an enlarged view of portion 10 shown in FIG. 1; FIG. 11 is an enlarged view of portion 11 shown in FIG. 1; and,

FIG. 12 is an enlarged view of portion 12 shown in FIG. 7. The dash-dash broken lines in the drawings depict portions of the water flosser that form no part of the claimed design. The dot-dash broken lines represent boundaries of the enlarged portions and form no part of the claimed design.

1 Claim, 12 Drawing Sheets
